ARRANGEMENT FOR AUTOMATICALLY
STEERING A SHIP ON A PREDETER-
MINED COURSE

John Alexander Dias, Bandra, Bombay, India

Application November 19, 1948, Serial No. 60,854
In Great Britain September 10, 1945

10 Claims. (Cl. 318—489)

1

This invention relates to devices for automatically steering a ship on a predetermined and pre-set course. This application is a continuation-in-part of application Serial No. 637,709, filed December 28, 1945, now abandoned.

This invention has for its objects to provide means whereby such automatic steering is instantaneously effected should the ship deviate from the pre-set course.

The arrangement also provides for electrically steering the ship by hand operation when bringing the ship into or out of harbor or when the ship is in a congested traffic lane.

The arrangement can also, with modification, be successfully applied to aircraft, particularly when such craft are to be flown long distances, and thereby relieve the navigator should it be necessary for him to leave his seat and attend to other matters.

According to the invention, there is provided an arrangement for automatically steering a ship on a predetermined and pre-set course in which an electric control is actuated should the ship deviate from the pre-set course. Briefly, the arrangement comprises means to stop the functioning of either of two separate photoelectric cells, independent of each other, by interrupting separate light beams to said cells and which are reflected by mirrors carried on the magnetic needles of two compasses. The photoelectric cells, when inactive one at a time, cause two separate relays to complete two separate circuits which, in turn, actuate a single field motor that is geared to the steering wheel shaft, whereby the steering apparatus is moved in the required direction to adjust such deviation of the pre-set course.

A feature of the invention is that the magnetic compass needles, preferably of the laminated type, are set to the desired direction by swivel stops mounted on a friction grip ring, marked with cardinal points of the compass, which may be slipped onto the periphery of the compass stand.

In the preferred arrangement, the photoelectric cells, which are actuated by light beams reflected from mirrors carried by either of the magnetic needles, cause, when inactive, a series of relays to complete a selected electric circuit to a single field motor. The circuit from the port relays cause the motor to rotate in one direction and turn the rudder to starboard, while the circuit from the starboard relays cause the motor to rotate in the opposite direction to turn the rudder to port.

A leading screw, turned by the motor simul-

2

taneously with the rudder, slides a block which operates two self-retracting limit switches, one at each end of the screw bed, which are movably mounted to permit adjusting the distance to be moved for operating the limit switches for cutting the electric motor circuit when the rudder reaches a pre-set angle, either port or starboard. The system is provided with alarms which selectively ring when the respective lamp circuits fail.

10 The novel features that are considered characteristic of the invention are set forth with particularity in the appended claims. The invention itself, however, both as to its organization and its method of operation, together with additional objects and advantages thereof, will best be understood from the following description of specific embodiments when read in connection with the accompanying drawings, wherein like reference characters indicate like parts throughout

20 the several figures and in which:

Fig. 1 is a diagrammatic layout of the preferred embodiment of the invention;

Fig. 2 is a cross-sectional view taken axially of a compass in accordance with the present invention;

Fig. 3 is a plan view of the steering shaft control mechanism including the adjustable limit switches;

Fig. 4 is a diagrammatic layout of a photoelectric cell circuit; and

Fig. 5 is a diagrammatic layout of a modified arrangement of the invention.

Referring now to the drawings, specifically to Fig. 1, the present invention contemplates the automatic adjustment of the shaft S, which may be the steering wheel or the rudder shaft, to automatically maintain the craft on a pre-set course. According to a preferred embodiment, the invention comprises a pair of compasses I and I' which are specially adapted to selectively control a reversible electric circuit for selectively energizing a reversible motor 2 which drives a worm 3 that is in mesh with a follower 4 on the shaft S.

45 The compasses I and I' are identical in construction, as best shown in Figs. 1 and 2. One of these compasses, compass I, will control deviations of the craft to port from the pre-set course and the other, compass I', will control deviations to starboard. Each of these compasses is adapted to be set to maintain the craft on a predetermined course within limited degrees on their respective port and starboard sides.

The compasses I and I' respectively comprise a stand 5—5' which supports the compass post

6—6' on which the magnetic needle 7—7' is journaled. In the present instance, a laminated needle structure is preferred. A pair of mirrors 8—8' and 9—9' are vertically mounted on the needle 7—7', back-to-back and on opposite sides of the pivotal axis of the needle 7—7'. A friction ring 10—10' is movably mounted around the periphery of the compass post 6—6' and has the cardinal points of the compass indicated thereon. An adjustable swivel stop tongue 11—11' is mounted on the friction ring 10—10', preferably at the north point on the ring, and is adapted to extend into the path of the magnetic needle 7—7'.

A collar 12—12' is mounted around the stand 5—5' and may be fixed in circumferential adjustment by a thumb screw 13—13'. The collar 12—12' supports three radially extending bracket arms 15—15', 16—16' and 17—17' which respectively support a lamp house 18—18', a photoelectric cell 19—19' and a counter-weight 20—20'. The lamp house 18—18' and photocell 19—19' are positioned in a plane intersecting the mirrors 8—8' and 9—9' and are supported by their brackets 15—15' and 16—16' to be directed at right angles to each other. The compass post 6—6' is provided with a plurality of pin holes 21—21' arranged in a circle and adapted to selectively receive pins for restraining the needle 7—7' during the course pre-setting operation.

The photocells 19 and 19' are respectively connected by conductors 22 and 22' with main lines 23 and 23' and by conductors 24 and 24' with electro-magnetic relays 25 and 25'. The circuits for the photo-electric cells 19 and 19' are best shown in Fig. 4. When the light beams from the lamps 18 or 18' strike the respective cell, the current generated by it passes through resistances B and C, on to the potentiometer D and to conductors 24 or 24'.

The photocells 19 and 19' respectively energize the relays 25 and 25' when the cells are activated by the respective light beams reflected by the mirrors 8 and 8' or 9 and 9' from the lamps 18 and 18', and when the needles 7 and 7' pivot to swing the mirrors 8 and 8' or 9 and 9' so that the light beams are cut off or reflected away from the photocells 19 or 19', the respective cell is inactivated which, in turn, de-energizes the respective relay 25 or 25'.

The relays 25 and 25' control the operation of the reversible circuits through the motor 2, and, as these relays are controlled by the photocells 19 and 19' which are operable by the lamps 18 and 18', it is imperative that the lamps be provided with alarm circuits. Consequently, the lamps 18 and 18' are respectively supplied from main line 23 by conductors 50 and 50' and manually operable switches 51 and 51', and are respectively connected by conductors 52 and 52', through electro-magnetic relays 53 and 53', to main line 23'.

The relays 53 and 53' respectively control switches 54 and 54' which are interposed in conductors 55 and 55' between signals or alarms 56 and 56' and the main line 23'. The alarms 56 and 56' are respectively connected to main line 23 by conductors 57 and 57' and manually operable switches 58 and 58'. Thus, when the lamps 18 and 18' are energized by closing manual switches 51 and 51', the relays 53 and 53' are energized unless the lamp circuits are broken. When manual switches 58 and 58' are closed, the circuits are completed through the alarms 56 and 56' except for the relay switches 54 and 54', which are opened when the relays

53 and 53' are energized or automatically closed when the relays are de-energized by the breaking of the lamp circuits.

The photocell controlled relays 25 and 25' respectively control switches 26 and 26' which are connected on one side by conductors 27 and 27' to one of the main lines 23' and on the other side to conductors 28 and 28' which extend to one pole 29a and 29a' of manually operable double pole switches 29 and 29'. The other poles 29b and 29b' of the switches 29 and 29' are connected by conductors 30 and 30' directly to the main line 23'. The switches 29 and 29' are connected by conductors 31 and 31' with limit switches 32 and 32' which are connected by conductors 33 and 33' that extend through relays 34 and 34' to the other of the main lines 23.

The electro-magnetic relays 34 and 34' control, through levers 35 and 35', the operation of a reversing switch 36 which includes fixed contacts 36a and 36a' and 36b and 36b', and movable contacts 36c and 36c' which are biased in opposite directions to intermediate, inactive or neutral position by springs 37 and 37'. The reversing switch 36 controls both the operation and the reversing of the field of the motor 2. The movable contact 36c' is connected by conductor 38 with main line 23' and the other movable contact 36c is connected by conductor 39 to the motor 2 which, in turn, is connected by conductor 40 with main line 23.

The pairs of fixed contacts of the switch 36 are interconnected through the field 2a of the motor 2. The contact 36a is connected by conductor 41 with the field 2a which, in turn, is connected by conductor 42 with contact 36a'. Contact 36b is connected by conductor 43 with contact 36a' and field conductor 42, and contact 36b' is connected by conductor 44 with contact 36a and conductor 41.

Thus, if the switch 36 is closed by relay 34' with the a contacts, the motor 2 and field 2a is energized by a circuit from main line 23 through conductor 40, motor 2, conductor 39, movable contact 36c, fixed contact 36a, conductor 41, field 2a, conductor 42, fixed contact 36a', movable contact 36c', and conductor 38 to main line 23'.

Conversely, if the switch 36 is closed by relay 34 with the b contacts, a circuit is completed from main line 23 through conductor 40, motor 2, conductor 39, movable contact 36c, fixed contact 36a, fixed contact 36b, conductor 43, fixed contact 36a', conductor 42, field 2a, conductor 41, fixed contact 36a, conductor 44, fixed contact 36b', movable contact 36c' and conductor 38 to main line 23'.

It will be seen that the circuit through the motor 2 and movable contacts 36c and 36c' remains the same regardless of the direction 60 through the field 2a. Furthermore, the field 2a is directly connected only to the fixed contacts 36a and 36a', but the direction of current flow therethrough may be reversed. Therefore, to clarify, the connection through the field 2a, forward circuit F is shown in Fig. 1 by arrows extending from contact 36a, conductor 41, field 2a, and conductor 42 to fixed contact 36a', and reverse circuit R is shown by arrows from contact 36b, conductors 43 and 42, field 2a and conductors 41 and 44 to contact 36b'.

When a circuit is completed through motor 2, it drives the worm 3 which rotates the follower 4 which then turns the shaft S. If desired, a gear change system 60, controlled by a manually operable lever 61, may be interposed between

the motor 2 and worm 3. The follower 4 may be connected to the shaft S by a clutch 62 that is manually operable by a lever 63 to permit manual operation of the shaft S. When the clutch 62 is closed, the shaft S will be driven by the motor 2 when a motor circuit is closed and as long as the circuit remains closed.

The operation of the motor is limited, however, by the limit switches 32 and 32' in the circuits controlling the reversing switch 36. The reversing switch 36 is normally maintained in neutral position by its springs 37 and 37'. It is moved to close a motor circuit by the operation of one of the relays 34 or 34'. The circuits of these relays, however, include the limit switches 32 and 32' which are subject to the drive of the motor 2.

As best shown in Fig. 3, the limit switches 32 and 32' are carried by supports 70 and 70' that are slidably mounted within a slot 71 in a base plate 72. A leading screw or threaded rod 73 extends co-axially from the worm 3 above the plate 72 and parallel with the slot 71. A slide block 74 is threaded on the rod 73 with one end slidably anchored through a slot 75 in an upstanding flange 76 on the plate 72 and the other end aligned between the limit switches 32 and 32'. The plate 72 carries rudder angle indications along the slot 71, the indications starting with zero centrally of the length of the slot.

The switch supports 70 and 70' may be adjustably positioned along the slot 71 to the selected limit of rudder angulations. Then when the motor 2 is energized, it will drive the worm 3 and also turn the threaded rod 73 and thread the block 74 therealong it abuts and opens one of the limit switches 32 or 32', depending upon the direction of drive of the motor 2. The drive of the motor 2 and movement of the block 74 is such as to move the block toward the limit switch 32 or 32' that is in the circuit of the relay 34 or 34' which has been activated to close the reversing switch 36 and the motor circuit. Thus, when the block 74 opens the respective limit switch 32 or 32', the respective relay 34 or 34' is deenergized and permits the reversing switch 36 to be neutralized by its springs 37 and 37' and open the motor circuit.

A scribe 77 may be fixed to the protruding end of the sliding block 74 to scribe a line 78, representing the movement of the rudder fluctuations, on a strip of moving paper 79 as it is slowly moved by winding on a roll 80. When taken at intervals from point to point on the meridian and transferred to graphs, scribed line 78 will show a difference, if any, when compared with the pre-calculated position of the ship, and also facilitate correct positioning of rudder angle limit switches 32 and 32' to suit circumstances and conditions.

In the operation of the invention for automatic steering, it is predetermined while the ship is lying in dock or harbor, that the course is to be 45° due N. E. The operator therefore sets the port compass, by turning friction grip ring 10, bearing swivel stop tongue 11 and marked cardinal points, until the point 45° N. E. coincides with the fore line mark on the compass post 6. Next, he turns and secures the magnetic needle 7 flush with swivel tongue 11 by inserting a pin in one of the holes 21 on compass post 6, as shown in dotted line in Fig. 1. The lamp 18 is then energized by manually closing the switch 51, thereby energizing relay 53 and thus opening the circuit to the bell 56. The manual switch 58, in circuit with the bell or alarm 56, is then closed to complete the alarm circuit.

The arm support ring 12 is then turned about the stand 5 until the light beam from the lamp 18 is focussed by mirror 8 on photoelectric cell 19. This position of the ring or collar 12 is secured by tightening thumb screw 13. This position causes the cell 19 to act by its own current on relay 25 and open the switch 26. The securing pin may then be removed from the hole to allow the compass needle 7 to revert to its free position, thus turning the mirror 8 and cutting off the light beam from cell 19. This action causes the cell 19 to remain inactive, the result being that relay 25 ceases to function and allows switch 26 to close.

15 The friction grip ring 10', marked with cardinal points and bearing swivel tongue stop 11', is then turned about post 6' until the point 45° N. E. coincides with the fore line on compass post 6', allowing the magnetic needle 7' to turn with it, being flush with the stop 11', due to its magnetic force. The lamp 18' is then energized by manually closing switch 51', thereby energizing relay 53' and causing it to break the circuit to the bell 56' by opening the switch 54'. The manual switch 58', in circuit with the bell 56', may then be closed.

20 The arm support 12' is then adjusted on the stand 5' to focus the light beam from the lamp 18' through the mirror 8' onto the photoelectric cell 19', in which position the ring or collar 12' is locked by turning thumb screw 13'. The photocell circuit being completed by the incidence of the light beam, it will act on relay 25' which in turn will open the switch 26'. The final 25 position of the parts of the compasses 1 and 1', as pre-set to course and described above, are shown in Fig. 1.

25 The limit switches 32 and 32' are pre-set along the slot 71 to cut off the circuits of the relays 34 and 34' when the rudder is 60° starboard and 30° port, respectively. The automatic steering mechanism is now completely set except for the manual switches 23 and 29' which may be closed with poles 29a and 29a' for automatic, or poles 29b and 29b' for hand operation. As shown in 40 Fig. 1, these switches are closed in automatic position; however, they are operated by hand with poles 29b and 29b' to take the ship out of dock or harbor.

45 Upon moving switch 29 to terminal 29b, it completes a circuit directly from main line 23 through relay 34 which, in turn, switches on field reversing switch 36 from neutral to terminals 36b and 36b', completing circuit R (Fig. 1), causing 50 electric motor 2 to rotate in one direction and turn the rudder to starboard. On cutting off switch 29, field reversing switch 36 is pushed back to neutral by spring 37. Similarly, on turning switch 29' to terminal 29b', it completes a circuit 55 directly from main line 23 through relay 34' which, in turn, switches field reversing switch 36 to the opposite set of terminals 36a and 36a', thus completing circuit F (Fig. 1), but motor 2 rotates in the opposite direction, turning the rudder to port. On cutting off switch 29', the field 60 reversing switch 36 is pushed back to neutral position by spring 37'.

65 This action of motor 2 is transmitted through multiple changed gear box 60 to worm 3 and worm wheel 4 to horizontal steering wheel shaft S which causes the steering engine to operate. As leading screw 73, fixed to worm 3, turns in either direction, it slides block 74 toward one of the limit switches 32 or 32' to break the circuit 70 through the respective relay 34 or 34'. Any

necessary alterations in rudder angle settings or steering wheel shaft speeds, the former by shifting limit switches 32 and 32' and the latter by gear shift lever 61 on multiple gear box 60, can be made to suit altered conditions while the ship is on its course.

Having pre-set all the components to a pre-determined course before starting, the ship may be taken out of the decks or harbor by manually operating switches 29 and 29', to steer the ship to starboard or port by closing with corresponding poles 29b and 29b'. While the ship is going in other than the pre-set direction, as shown in Fig. 1, one of the magnetic compass needles 7 or 7' will be flush with its swivel tongue stop 11 or 11', on account of its magnetic force. When out of port, the switches 29 and 29' may be shifted to automatic terminals 29a and 29a', as shown in Fig. 1, whereupon the ship will immediately steer automatically in the direction pre-set by the swivel tongue stops 11 and 11'.

In the position shown in Fig. 1, the light beam from lamp 18 is cut off from the photoelectric cell 19, due to deviation of magnetic needle 7, which carries the mirror 8, thus causing the cell 19 and relay 25 to be inactive and permitting the switch 26 to close. The closing of switch 26 completes the circuit through pole 29a, switch 29, limit switch 32 and relay 34, to act on field reversing switch 36 and complete circuit R with the current running in one direction of the field coil 2a. Fig. 1 shows starting position of mechanism at this stage.

The completion of circuit R actuates the motor 2, which, in turn, causes the rudder to swing to starboard through multiple gear box 60, worm 3 and worm wheel 4 to steering wheel shaft S. The action of motor 2 simultaneously turns leading screw 73 which slides block 74 to starboard, allowing the rudder, if necessary, to reach the pre-set angle of 60° starboard, when limit switch 32 opens up the circuit through the relay 34, thus stepping the motor 2 from rotating further. Upon deenergization of relay 34, reversing switch 36 is pushed back by the spring 37 to neutral position.

Likewise when the ship swings to starboard from its course, magnetic needles 7', carrying mirror 8', will deviate and cut off the light beam from lamp 18' on photoelectric cell 19', causing the cell 19' and relay 25' to be inactive. Switch 26' is then automatically closed to complete the circuit through relay 34', which will cause field reversing switch 36 to connect with the opposite set of terminals. The current will now flow through the same field coil 2a but in an opposite direction, circuit F, thus reversing the motor 2 to cause swinging of the rudder to port. Simultaneously leading screw 73 will reverse the slide block 74 to port for acting on retracting switch 32' to open up the circuit through relay 34', should the rudder reach the pre-set angle 30° port.

For return voyages on the course, rudder angles and steering wheel shaft speed gears may be reset to suit conditions. While turning, the magnetic needles 7 and 7' may be permitted to swerve around by lifting swivel tongue stops 11 and 11'. Mirrors 9 and 9' will then reflect the light beams to the photoelectric cells 19 and 19'. Direction and pre-setting of course are then read from cardinal points coinciding with the aft line marks on compass posts 6 and 6'.

As a further test that the apparatus is operative and fully automatic, open switches 51 and

51' to switch off lamps 18 and 18'. Steer the ship to any position and reset rudder angles, if necessary, to suit conditions caused by extent of deviation for return to pre-set course. With one of the magnetic needles either 7 or 7' lying flush with its respective swivel tongue stop 11 or 11', switch on the lamps 18 and 18'. The ship will immediately steer automatically towards the course and maintain the pre-set, predetermined and desired course.

Several pairs of compass sets may be connected to the same automatic steering mechanism, especially at stem and stern, to secure true and more accurate alignment of the ship with its predetermined and pre-set course. This arrangement is shown in Fig. 5, the components being duplicated throughout the several pairs of compasses.

The worm wheel 4, or its section, can be fixed directly on the rudder post, instead of the steering wheel shaft, and engaged by a clutch, leaving automatic and hand control switches for operation on the navigation deck.

All relays are, preferably, magnetically sealed to shield the compass magnets.

The electric circuits illustrated in the drawings are for direct current single field motors but suitable modification can be made for three-phase alternating current motors without departing from the scope of the invention.

Adjustments to suit weather and sea conditions are achieved by gear changes and settings of limit switches 32 and 32' to stabilize either port or starboard rudder angle position individually.

Although certain specific embodiments of the invention have been shown and described, it is obvious that many modifications thereof are possible. The invention, therefore, is not to be restricted except in so far as is necessitated by the prior art and by the spirit of the appended claims.

40 What I claim is:

1. Apparatus for steering a craft on a pre-selected course, which apparatus comprises a reversible electric motor operatively connected to a shaft of the steering mechanism of a craft, an electric circuit for selectively energizing said motor, two photoelectric cells subject to activation by light beams for selectively controlling said motor circuit, a pair of compasses, means for supporting one of said cells in selected position relative to each of said compasses, and reflectors carried on the magnets of said compasses for respectively reflecting light beams toward said photoelectric cells when said magnets are in certain angular positions.

55 2. Apparatus for steering a craft on a pre-selected course, which apparatus comprises a reversible electric motor operatively connected to a shaft of the steering mechanism of a craft, an electric circuit for selectively energizing said motor, two photoelectric cells subject to activation by light beams for selectively decontrolling said motor circuit, a pair of compasses, means for supporting one of said cells in selected position relative to each of said compasses, and reflectors

60 carried on the magnets of said compasses for respectively reflecting light beams toward said photoelectric cells when said magnets are in proper angular positions while the craft is on the pre-selected course.

65 3. Control apparatus which comprises a control shaft to be turned, a reversible electric motor operatively connected to said shaft, an electric circuit for selectively energizing said motor to turn said shaft, two photoelectric cells subject to activation by light beams for selectively con-

trolling said motor circuit, a pair of compasses, means for supporting one of said cells in selected position relative to each of said compasses, reflectors carried on the magnets of said compasses for respectively reflecting light beams toward said photoelectric cells when said magnets are in certain angular positions, a pair of limit switches in said circuit for de-energizing said motor, and means operated by said motor simultaneously with the driving of said shaft for operating one of said limit switches to deenergize said motor after a selected time.

4. Control apparatus as defined in claim 3 wherein said limit switches are spaced in opposed relation and said motor operated means includes a member movable in alignment with and between said switches.

5. Control apparatus as defined in claim 4 wherein said limit switches are adjustably positioned to enable variable spacing, and said motor operated means includes a threaded rod driven by said motor and supporting said movable member.

6. Control apparatus as defined in claim 3 wherein said motor is operatively connected to said shaft by a manually operable clutch.

7. Control apparatus comprising a circuit to be controlled, means for energizing said circuit, two photoelectric cells subject to activation by light beams for selectively controlling said means, a pair of compasses, means for supporting one of said cells in selected position relative to each of said compasses, and reflectors carried on the magnets of said compasses for respectively reflecting light beams toward said photoelectric cells when said magnets are in certain angular positions.

8. Control apparatus comprising alternate circuits to be controlled, means for energizing each

of said circuits, a photoelectric cell for controlling each of said means, two compasses each including a magnet, means for supporting one of said cells in selected position relative to each of said compasses, a stop adjustably positioned in the path of the magnet of each compass to limit the movement of its magnet in one direction, the stops being on opposite sides of their respective magnets, and reflectors carried on the magnets for respectively reflecting light beams toward the photo-electric cell associated therewith when abutting said stops.

9. Control apparatus as defined in claim 8 wherein said stops are pivotally mounted on rings which have the cardinal points marked thereon and which are respectively movable about the peripheries of said compasses.

10. Control apparatus comprising alternate circuits to be controlled, means for energizing each of said circuits, relays for respectively controlling each of said means to deenergize the circuits when the relays are energized, two photoelectric cells for energizing said relays when said cells are activated by the impingement of light beams, two compasses each including a magnet, means for supporting one of said cells in selected positions relative to each of said compasses, a stop adjustably positioned in the path of the magnet of each compass to limit the movement of its magnet in one direction, the stops being on opposite sides of their respective magnets, and reflectors carried on the magnets for respectively reflecting light beams toward the photo-electric cell associated therewith when abutting said stops.

JOHN ALEXANDER DIAS.
